EGG CARTON

David L. Pearl, Atlanta, and John G. Waller, College Park, Ga., and Beverly P. Head, Jr., Birmingham, Ala., assignors to W. R. Grace & Co., Duncan, S.C.

Continuation of abandoned design application Ser. No. 18,113, July 8, 1969. This application Sept. 1, 1970, Ser. No. 24,803

Term of patent 14 years

Int. Cl. D9—03

U.S. Cl. D9—190

FIG. 1 is a front-side perspective view of an egg carton showing our new design in an opened condition;

FIG. 2 is a front-side-top perspective view of the egg carton shown in FIG. 1 in a closed condition;

FIG. 3 is a rear side-bottom perspective view of the other side of the egg carton shown in FIG. 2; and

FIG. 4 is a transverse cross-sectional view showing the interior of the egg carton shown in FIGS. 1-3 the section being taken transversely of the carton through the central portion of two adjacent egg pockets.

This application is a continuation of design application Ser. No. D. 18,113, filed July 8, 1969, and now abandoned.

We claim:

The ornamental design for an egg carton, substantially as shown and described.
